UNITED STATES PATENT OFFICE.

HILMER N. ENHOLM, OF BUSHNELL, ILLINOIS.

WATER-ELEVATOR.

1,365,901.

Specification of Letters Patent. Patented Jan. 18, 1921.

Application filed November 6, 1918. Serial No. 261,375.

To all whom it may concern:

Be it known that I, HILMER N. ENHOLM, a citizen of the United States, residing at Bushnell, in the county of McDonough and 5 State of Illinois, have invented certain new and useful Improvements in Water-Elevators, of which the following is a specification.

This invention seeks to provide a simple 10 and easily operated mechanism whereby water may be raised from a well.

The invention is illustrated in the accompanying drawings, in which—

Figure 1 is a view partly in section and 15 partly in side elevation of my improved mechanism in position in a well;

Fig. 2 is an enlarged sectional view of the cylinder through which the lifting buckets or floats pass to enter the water.

20 The well 1 may be built in any well-known manner and is provided with a curb or hood 2 in the sides of which is mounted a shaft 3 carrying a sprocket wheel or pulley 4 around which is trained an endless chain 25 of floats or buckets 5. The curb 2 is equipped with a delivery spout 6 extending laterally from one side and a gate 7 may be provided to prevent the access of dust or other matter to the well when the elevator 30 is not in operation.

Within the well, I provide a plurality of brackets 8 to which I secure a pipe 9 which provides a vertical member 10 having an open upper end located above the 35 normal level of the water, indicated at 11. At the lower end of the said inlet member 10 is a return bend 12 which connects the pipe with a vertical cylinder 13, said cylinder being provided with an outer wall 14 40 and an inner wall 15 consisting of superposed axially aligned sections. Between the meeting ends of the sections of the wall 15, I interpose packing or washers 16 of leather or similar material which have their inner 45 edges projected into the bore of the sections so that they will bear upon the floats or buckets 5 and effect a water seal therewith to prevent the entrance of water into the cylinder. The outer wall 14 of the cylinder 50 is constructed with an annular inwardly projecting shoulder 17 at its lower end upon which is secured a collar or lugs 18 to which the lower end of the lowermost section of the inner wall 15 is secured. In the upper end 55 of the outer cylindrical wall 14 I secure a

collar or ring 19 which fits closely around the uppermost section 15 and in the said ring or collar 19 I mount adjusting screws 20. These adjusting screws have their lower ends bearing upon lugs or brackets 21 on the 60 side of the uppermost section 15 and it will be readily understood that by properly turning the screws, pressure will be exerted upon the said lugs so that the several sections of the inner cylindrical wall will be 65 forced together and securely clamp the washers or packing rings 16.

The water-elevating members 5 are hollow substantially cylindrical bodies having a flat head 22 at one end and at the opposite end having a cup-shaped head 23 which extends into the body as clearly shown in Fig. 2. The heads are both formed integral with the side walls of the body or permanently sealed therein so that the body will 70 be air-tight and I prefer to exhaust the air in the course of manufacture so that the interior of the bodies will be practically vacuums. The adjacent bodies are flexibly connected by rings 24 so that an endless chain 75 will be formed, and the bodies are so disposed that the concave or cup-shaped end will be uppermost as the body rises through and from the water. The water-elevating members should be of such dimensions that 80 they will fit closely within the several packing rings 16 and at least two of said members will be within the cylinder at all times. 85

It is thought the operation of the device will be readily understood. The several hollow bodies pass downwardly through the branch 10 of the pipe 9 and move upwardly 90 through the cylinder 13, the result being that the water in the well will flow into the cups at the upper ends of the several bodies 95 and each body will consequently lift a certain quantity of the water which will be delivered into the spout 6 as the several bodies pass over the pulley or wheel 4. The branch 10 of the pipe 9 serves to guide the water-elevating members as they pass down into the well and holds the pressure of the water from the same so that they will move in a rectilinear path to the return bend 12. The water cannot enter the cylinder 13 and there- 100 by reach the pipe 9, inasmuch as the engagement of the water-elevating members with the packing rings 16 forms an effectual water seal and any small quantity of the water 105 which may possibly enter the upper ex- 110

tremity of the cylinder will be immediately caught by the cup-shaped upper end of the member 5 which may be immediately adjacent the top of the cylinder. As the said members 5 are free in the open water above the cylinder 13, the strain upon the operating mechanism will be minimized and the water will be raised rapidly and easily and without any particular effort.

- 10 10 In the use of the improved water elevating apparatus, the operation of the handle or crank 25 of the wheel results in the movement of the endless chain over the wheel whereby the hollow air-tight bodies upon 15 leaving the cylinder 13 will pick up a quantity of the water and discharge the same through the spout 6. During the downward movement of the buckets or hollow bodies, the same are spaced from contact with the 20 water so as to remove the resistance which would otherwise be offered to the buckets on their downward movement.

Having thus described my invention, what is claimed as new is:

- 25 1. The combination with a well, of a wheel arranged at the upper end of the well and having operating means, an endless chain trained over said wheel and comprising a plurality of hollow air-tight bodies and 30 means connecting the bodies, one end of each body being cup shaped for forming water receiving means, a pipe receiving said chain and formed adjacent one end with a bend thereby forming a long chain inlet branch 35 terminating above the level of the water in the well and a short outlet branch terminating below the water level, and a cylinder arranged at the discharge end of said outlet branch and having means providing a water-

tight connection between the same and the 40 hollow air-tight bodies.

2. A water elevating apparatus for wells comprising a wheel having operating means, an endless chain trained over said wheel and comprising a plurality of hollow air-tight 45 bodies and means connecting the bodies, one end of each body being cup shaped for forming water receiving means, a pipe receiving said chain and formed adjacent one end with a bend thereby forming long and short 50 branches, said long branch terminating above the level of the water in the well and constituting a chain receiving means, said short branch terminating below the level of the water and constituting a chain outlet 55 means, and means to exclude water from said short branch.

3. In a water-elevating apparatus, the combination of a pipe to be secured within a well and having two vertical members connected by a return bend, one of said vertical members having its upper end above the water level in the well and the other vertical member having its upper end below the water level, a cylinder within the shorter 65 branch of said pipe consisting of a plurality of axially aligned superposed sections, packing between the meeting ends of adjacent sections, means for clamping said sections against the packing, an endless chain of 70 water-elevating members movable downwardly through the longer branch of the pipe and upwardly through the said cylindrical sections, and operating means connected to said water elevating means. 75

In testimony whereof I affix my signature.

HILMER N. ENHOLM. [L.S.]
